UNITED STATES PATENT OFFICE.

CHARLES J. HODGE, OF Houghton, Michigan.

DESIGN FOR A FRAME FOR SUPPORTING ORE OR MINERAL WASHING JIG-SCREENS.

SPECIFICATION forming part of Design No. 29,929, dated January 3, 1899.

Application filed December 12, 1898. Serial No. 699,069. Term of patent 7 years.

To all whom it may concern:

Be it known that I, CHARLES J. HODGE, a citizen of the United States, residing at Houghton, in the county of Houghton and State of Michigan, have invented and produced a certain new and original Design or Useful Shape for a Frame for Supporting Ore or Mineral Washing Jig-Screens, of which the following, in connection with the accompanying drawings, is a full, clear, and exact specification.

In the said drawings, Figure 1 is a plan view of a frame of the character described embodying design; and Fig. 2 is a side elevation thereof, partly in section, on the irregular line 2 2.

The leading features of my design consist of the marginal frame portion A, surrounding the series of intermerged circular webs B, constituting a number of circles arranged one on each side of a number of four-sided figures C, which latter are formed by the contiguous edges of the four webs B. The webs B are very thin as compared with their depth, and they are coterminous in depth with the depth of the frame A, their upper and lower edges being flush with or in the same plane as the

upper and lower edges of the frame A. The webs B are also tapered from bottom to top, and their upper edges are rounded. The webs B also merge into the frame A, and the inner sides of the frame A are rounded or beveled throughout, as shown at D, with the exception of the places where the webs merge therewith and also with the exception of the places where bosses a are formed on the inner sides of the frame. The bosses a surround circular sockets a', formed at short intervals throughout the frame A.

Formed at one end of the frame and at the junction of two of the circular webs B is a circular perforated boss E.

Having thus described my invention, what I claim as new therein, and desire to secure by Letters Patent, is—

The design for a frame for supporting ore or mineral washing jig-screens substantially as herein shown and described.

CHARLES J. HODGE.
